Primary Examiner—Stella Reid*Assistant Examiner*—Carol Rademaker(74) *Attorney, Agent, or Firm*—Norris McLaughlin & Marcus PA(57) **CLAIM**

The ornamental design for a bottle, as shown and described.

DESCRIPTION

FIG. 1 is a top, front, right perspective view of the bottle;
 FIG. 2 is a rear elevational view thereof;
 FIG. 3 is a left side elevational view thereof;
 FIG. 4 is a top plan view thereof; and,
 FIG. 5 is a bottom plan view thereof.

The broken lines shown in the drawing figures are for environmental purposes only and form no part of the claimed design.
